AUTOMATICALLY OPERATED HEATER

Edwin S. Kant, Brookline, Mass.

Application December 30, 1932, Serial No. 649,519

7 Claims. (Cl. 110—36)

This invention relates to improvements in furnace constructions, and the general object thereof is to provide automatic feeding mechanism which will maintain an even and uniform fire in the grate of a furnace.

A further object of the invention is to provide means operable in conjunction with the feeding mechanism for supplying a current of air below the grate of the furnace, with means for simultaneously controlling the fuel feed and the current of air in such a manner that the heat delivered from the furnace may be regulated.

Another object of the invention is to provide thermostatically operable means for controlling the fuel-feeding means and preferably also the air current producing means in response to variations in temperature in a room being heated.

A further object of the invention is to provide thermostatically operable means responsive to the temperature of the water in a water heater or boiler within a furnace and operable to control the supply of fuel and preferably also to control said current of air.

A further object of the invention is to provide automatic fuel feeding mechanism for a furnace comprising a central circular grate, a rotatable stoker ring concentric therewith, means for depositing fuel upon the stoker ring, and means for delivering the fuel from the stoker ring to the periphery of the fire-bed and preferably so constructed as progressively to deliver the fuel uniformly throughout the desired circumference of the fire-bed.

While any suitable means may be provided for continuously depositing fuel upon the stoker ring, in the illustrative embodiment of the invention disclosed herein, which is designed particularly for a household furnace, fuel is delivered to the stoker ring from a magazine adapted to be filled with coal, coke, or other combustible fuel.

A further object of the invention is to provide a furnace, preferably of the type above described, with a novel water heater or boiler of relatively economical construction and efficient operation.

These and other objects and features of the invention will more fully appear from the following description and the accompanying drawings, and will be particularly pointed out in the claims.

In the drawings:

Fig. 1 is a view, mainly in vertical section, of the furnace embodying the invention and provided with a water heater;

Fig. 2 is a sectional view on line 2—2 Fig. 1;

Fig. 3 is a sectional view of mechanism for maintaining the periphery of the stoker ring in firm engagement with the rotatable driving member, on line 3—3 Fig. 2;

Fig. 4 is a view, partly in vertical section and partly in elevation, of the heating unit, means for supplying the same with water, and a reservoir or steam chamber communicating with the upper end of the heating unit;

Fig. 5 is a transverse sectional view on line 5—5 Fig. 4, through one of the units, and a part of an associated unit of the heater; and,

Fig. 6 is a plan view of one of the assembled heating units.

The heater construction illustrated in the accompanying drawings comprises a rectangular frame structure, preferably having vertical angle irons 1 connected by horizontal angle irons 2 and end angle irons 3 to provide a rigid frame construction. A suitable sheet metal casing 4 extends around the angle iron structure to enclose the same, and desirably is provided with a door 5 to permit access to the furnace for the purpose of building a fire therein. Horizontal girders 6, 7, and 8, and a transverse girder 9, which is supported upon supplemental standards 10, serve to support a rotatable stoker ring 11. Preferably three brackets 12, having journaled therein anti-friction rollers 13, are mounted upon the girders 6, 7, and 8, in such a manner that the stoker ring rests upon the rollers 13, thereby permitting the stoker ring to be readily rotated.

The furnace is provided with a preferably upwardly convex central grate 14 which is carried upon transverse girders 15 supported at their ends upon the girders 7 and 8. A supplemental grate 16, which preferably is of inverted conoidal construction presenting downwardly curved inner walls, is supported in a countersink 17 in the inner periphery of the stoker ring, and desirably is secured to the stoker ring in such a manner that rotation of the stoker ring will rotate the supplemental grate 16. However, other forms of grate construction may be employed within the spirit and scope of the invention.

The front end of the furnace construction is provided with a chamber 18 forming a magazine for fuel, such as coal or coke, and the lower end of the magazine is tapered to provide a chute 19, the lower end of which spans the stoker ring 11 and is provided with an aperture in its side to permit the fuel to be continuously deposited upon the stoker ring during the rotation thereof.

Any suitable means may be provided for rotat-

ing the stoker ring. In the preferred construction illustrated herein a rotatable driving member 20 may frictionally engage the periphery of the stoker ring, or if desired more positive engagement may be provided by intermeshing gear teeth upon the periphery of the stoker ring, and upon the rotatable driving member 20. The rotatable driving member 20 is fixedly secured to the upper end of a shaft 21 which is rotatably mounted in ears extending from a bracket 22 which is fixedly secured to the transverse girder 9. A beveled gear 23, which is fixedly secured to the lower end of the shaft 21, engages a beveled pinion 24 upon a horizontal shaft 25, which is mounted in suitable brackets 26 and 27 mounted upon a cross girder 28 preferably supported by the posts 10.

Any suitable means may be provided for driving the shaft 25. In the preferred construction illustrated the shaft 25 is driven by an electric motor 29, the shaft 30 of which transmits motion through suitable reduction gearing of usual type contained in a casing 31 to a pulley 32 which drives a belt 33 passing over a relatively large pulley 34 which is fixedly secured to the shaft 25.

It is obvious that the rotation of the motor shaft 30 may thus be utilized by the interposition of suitable reducing gears to drive the shaft 21 at any desired speed, and thereby impart to the stoker ring a desired rate of rotation.

Means desirably are provided for maintaining the periphery of the stoker ring in firm engagement with the rotatable member 20 so as to insure proper driving of the stoker ring, particularly when a frictional drive is employed. In the preferred construction illustrated rollers 35 and 36, mounted respectively on brackets 37 and 38 carried by the side girders 6 and 8, engage the periphery of the stoker ring at widely spaced intervals upon the opposite side of the stoker ring to the line of contact between the rotatable member 20 and the stoker ring. One of these rollers 36 desirably is so mounted that pressure may be continuously applied through the roller 36 so as to maintain the stoker ring in forcible engagement with the rotatable member 20, and the companion anti-friction roller 35. An illustrative mechanism for accomplishing this purpose is shown in Fig. 3, in which the roller 36 is provided with a split bushing 39 which is rotatably mounted upon the offset central portion 40 of a shaft 41 which is mounted at one end in a suitable aperture in an ear 42 extending upwardly from the bracket 38 and integral therewith. The other ear 43 of the bracket 38 desirably is made in two parts adapted to be assembled and secured together by a screw 44 after the end of the shaft has been inserted through the bracket ear 42. A yoke-shaped member 45, the arms 46 of which are provided at their ends with slotted bosses 47, is secured to the shaft 41 by pins passing through the bosses and the shaft. The central portion of the yoke-shaped member 45 is provided with a web upon which the lower end of a spiral spring 48 is seated. The upper end of the spring 48 abuts against a bracket 49 which is secured to the frame member 6. The spring 48 is positioned under compression and acts through the fork-shaped member to rotate the shaft 41, thereby causing its eccentric portion 40 to press the roller 36 firmly against the periphery of the stoker ring, and consequently to force the periphery of the stoker ring firmly into engagement with the rotatable driving member 20, and the complementary anti-friction roller 35, thus maintaining a

driving engagement between the rotatable member 20 and the stoker ring at all times.

One of the important objects of the invention is to provide means for progressively delivering fuel from the rotating stoker ring to the fire-bed. This is accomplished by providing a stationary deflector extending inwardly across the stoker ring and preferably in the form of a spiral of approximately three hundred sixty degrees length. As illustrated in the accompanying drawings, the deflector comprises a plate or vane 50 which extends from the wall of the magazine outlet spirally along and in proximity to the stoker ring in the direction of its rotation through approximately three hundred sixty degrees and forms the inner wall of the outlet of the fire box.

By reason of this construction the rotation of the stoker ring causes the fuel, which has accumulated thereupon, to be progressively shoved over the inner edge of the ring upon the periphery of the fire-bed, and as the spiral gradually approaches the inner periphery of the ring, the fuel is fed substantially uniformly throughout substantially the entire periphery of the fire-bed, or in other words, a complete stoker ring load is moved into the fire area in each revolution and the fuel is discharged upon the periphery of the fire-bed at substantially the same rate throughout each degree of the inner periphery of the ring, thereby giving a uniform bed of glowing coal.

In the preferred construction as above described the central grate 14 is circular and upwardly convex and provided with usual perforations. It is concentric to the stoker ring and in a lower plane. The conoidal frustum-shaped ring or supplemental grate 16 fills most of the spaces between the stoker ring and the grate, leaving a narrow annular space between its lower end and the fixed grate. The downwardly curved surface of the conoidal supplemental grate facilitates the movement of the fuel by the action of gravity toward the center, thereby relieving the spiral delivery member 50 of some of the work which otherwise would be imposed upon it. The fuel is gradually consumed as it proceeds toward the center, the ash sifting through the air holes in the grates. This tends to thin the fire-bed, but the travel of the fuel and ashes toward the center offsets any disadvantage which would otherwise accrue therefrom. The relative motion between the supplemental grate 16 and the central stationary grate 14 produces a grinding action, and the curvature of these parts, together with the narrow space between the grates, assists in the elimination of ash.

Preferably means, also driven from the motor 29, are provided for delivering a suitable current of air beneath the grate of the furnace to facilitate combustion. In the particular construction illustrated, the fan of a blower 51 is fixedly secured to the shaft 30 and delivers a current of air through a suitable pipe or conduit 52 into the ash pit beneath the grate. Some of this current of air passes upwardly through the grate 14 and the supplemental grate 16 and consequently through the fire-bed upon the grate, while the remainder of the current of air passes upwardly through the spaces 53 at the corners of the casing into the combustion chamber above the grate, which may be lined with fire-brick, or other insulating material, (not shown) in the usual manner.

By reason of this construction the blower is actuated concurrently with the actuation of the stoker ring, and the arrest of the motor causes

the cessation of the rotation of the stoker ring and the consequent feed of the material, and will also cause the cessation of the action of the blower, or if a suitable rheostat is placed in the circuit 5 supplying the electric current to the motor, diminution of the speed of the motor will likewise diminish the speed of rotation of the stoker ring, and will also diminish the speed of the blower, so that the action of the feeding mechanism and 10 blower may be readily co-ordinated with the demands of the furnace to produce the desired amount of heat.

Preferably thermostatically operated means are provided for controlling the motor. In the present 15 illustrative embodiment of the invention an electric current is supplied from a suitable source, as from commercial service lines 54 and 55 to a switch or rheostat box 56 from which conductors 57 and 58 lead to the motor 29. A suitable thermostat 59, located in a room to be heated, serves to control the position of the switch or rheostat and acts to break or reduce the current supplied to the motor when the temperature of the room exceeds a predetermined temperature. By reason 20 of this construction, therefore, the feeding of the fuel to the furnace, and also the current of air supplied to the furnace, is automatically regulated in such a manner that a substantially constant temperature may be maintained within the 25 room to be heated.

The furnace above described is adapted to be employed in hot air, hot water, or steam heating systems. As illustrated herein the invention is embodied in a furnace having a water heater 30 or boiler for a steam heating system and a further feature of the invention comprises a novel and economical heater formed of a plurality of units adapted when assembled to provide a plurality of series of water tubes having headers 35 at their ends communicating with the water supply and a boiler, and providing intermediate of the respective series of water tubes like series of fire tubes through which the products of combustion pass and are finally discharged from the 40 stack.

The heater comprises essentially a series of units each of which is constructed of complementary thin sheets 60 of rust, or corrosion-resisting iron or steel, having the general form of an inclined parallelogram, and provided with edge flanges 61 extending substantially throughout the entire periphery and adapted to be abutted and welded edge to edge to make a hermetically closed construction. The faces of the plates are 45 provided with outwardly extending parallel ribs 62 and inwardly extending parallel ribs 63 adapted to abut against each other when the complementary plates are in assembled position, as illustrated in Fig. 5. These ribs extend throughout the major portion of the plates, but terminate sufficiently short of the ends thereof to provide headers 64 and 65 communicating with the ends of the channels or water tubes 66, thus formed. The water tubes have sufficient slope to provide 50 rapid circulation of the water. While the units preferably are formed of sheet metal in the manner above described, such units, of course, may be formed as cored integral castings.

The heater comprises a series of these units so positioned that the outwardly extending ribs 62 are in abutment throughout their length, thereby providing in effect a series of fire tubes 67 through which the gaseous products of combustion may be circulated. By providing suitable baffles (not 55 shown) the gaseous products of combustion may

be caused to circulate in reverse directions through adjacent fire tubes or sets of fire tubes.

A suitable main header 68 communicates with the lower end of the header 64, while the upper end of the header 64 and likewise the upper end 5 of the header 65 desirably communicate through extensions 69 and 70 with a suitable boiler 71 from which steam may be delivered through an outlet pipe 72 to a radiator or other heating system. The main header 68, through which water 10 is supplied to the heater, may serve to support the heater upon a suitable base 73 resting upon the girder 6, or other suitable support. By suitable modification, the same heater construction may be employed for a hot water heating system.

It is desirable where a hot water or steam boiler is employed to provide thermostatic means for also controlling the action of the motor adapted to discontinue or to reduce the speed of rotation of the motor if the temperature of the water or steam exceeds a predetermined minimum. This may be readily accomplished by providing a thermostatic element 74, preferably of the expandible fluid type, extending into the boiler, 20 and subject to the temperature of the water or steam therein, and having a pipe 75 leading to mechanism for actuating the switch or rheostat in the box 56 to discontinue the action of the motor, or reduce its speed, in response to excessive 25 temperature of the boiler or steam, it being understood that excessive temperature of the steam would be caused by increase in pressure in the pipes carrying the steam to the various heat-radiating units.

It will be understood that the particular embodiment of the invention described herein is of an illustrative character and is not restrictive, and that various changes in form, construction and arrangement of parts may be made within 30 the spirit and scope of the following claims.

Having thus described the invention, what is claimed as new, and desired to be secured by Letters Patent, is:

1. A furnace construction having a combustion chamber provided with a central circular grate, a conoidal grate having inner walls which curve gradually downward to surround at its lower end, said central grate, a rotatable stoker ring surrounding the upper end of said conoidal grate, in the plane of said upper end, means for depositing fuel upon said stoker ring, driving means for rotating said stoker ring, means for progressively delivering the fuel from said stoker ring with substantial uniformity throughout the periphery of the fire-bed supported upon said conoidal grate, means operable by said driving means in synchronism with the rotation of said stoker ring to deliver a current of air beneath said grate and means for controlling said driving means whereby the amount of fuel delivered to the furnace and the air supplied beneath the grate will be conjointly regulated to control the rate of combustion of fuel in the furnace.

2. A furnace construction having a combustion chamber provided with a central circular grate, a downwardly converging conoidal grate surrounding at its lower end said central grate, a rotatable stoker ring surrounding said conoidal grate, having a flat upper surface flush with the upper end of said conoidal grate, a magazine having an outlet overlying said stoker ring for depositing fuel by gravity upon said stoker ring, driving means for rotating said stoker ring, means for progressively delivering the fuel from said 65 70 75

stoker ring to the peripheral surface of said grate, comprising a stationary distributor extending from approximately the position upon which fuel is deposited from said magazine upon 5 said stoker ring across said stoker ring in the direction of its movement and in a spiral-like curve of approximately three hundred sixty degrees in length and operable to deliver fuel with substantial uniformity throughout the peripheral surface of the grate to the downwardly 10 inclined conoidal portion thereof.

3. A furnace construction having a combustion chamber provided with a perforated, stationary central grate, an inverted conoidal rotatable grate concentrically surrounding at its 15 lower end said stationary grate, a horizontal rotatable annular stoker ring surrounding the upper end of said conoidal grate presenting a surface lying in the same plane as the periphery of said conoidal grate and having means engaging said stoker ring to cause conjoint rotation therewith, driving means for rotating said stoker ring, a magazine having an outlet overlying said stoker ring adapted to maintain a body of fuel 20 upon said stoker ring, and means for progressively delivering fuel from said stoker ring with substantial uniformity throughout the horizontal peripheral surface of said grate to the downwardly inclined conoidal portion of the grate 25 along which the burning fuel descends by the action of gravity.

4. A furnace construction having a combustion chamber provided with a central convex, circular, stationary perforated grate, an inverted conical rotatable grate concentrically surrounding at its 30 lower end said stationary grate, a rotatable stoker ring surrounding the upper end of said conical grate presenting a surface lying in the plane of the periphery of said conical grate and having means detachably engaging the peripheral portion of said conical grate to cause conjoint rotation therewith but adapted to permit removal or replacement of said rotatable grate and driving means for rotating said stoker ring.

5. A furnace construction comprising a combustion chamber provided with a central circular 35

grate, a rotatable stoker ring surrounding said grate, a magazine having an outlet positioned to deposit fuel upon said stoker ring, driving means for rotating said stoker ring including a rotatable member engaging the periphery of said stoker ring, means for forcibly maintaining said stoker ring in engagement with said rotary driving member, and means for progressively delivering the fuel from said stoker ring along the periphery of the fire-bed supported by said grate. 40

6. A furnace construction comprising a combustion chamber provided with a central circular grate, a rotatable stoker ring surrounding said grate, a magazine having an outlet positioned to deposit fuel upon said stoker ring, driving means for rotating said stoker ring including a rotatable member engaging the periphery of said stoker ring, in proximity to the outlet of said magazine, a plurality of anti-friction rollers engaging the periphery of said stoker ring at spaced intervals, 15 and resilient means acting through one of said anti-friction rollers to maintain the periphery of said stoker ring in firm engagement with said rotatable driving member. 20

7. A furnace construction comprising a central circular grate, a rotatable stoker ring surrounding said grate, a casing enclosing said stoker ring and extending above and below the same to provide a combustion chamber above said grate, and an ash pit below said grate, means for depositing fuel upon said stoker ring, driving means for rotating said stoker ring including a rotatable member engaging the periphery of said ring, an electric motor, speed-reducing mechanism for transmitting rotation from the shaft of said motor to said rotatable member, a blower actuated by said motor shaft, and means for delivering a current of air from said blower into said ash pit and means located beyond the periphery of said stoker ring establishing communication between said ash pit and said combustion chamber, whereby a portion of the air will pass through said grate and the remainder will pass into the combustion chamber above said grate. 30 35 40
